UNITED STATES PATENT OFFICE.

ALVIN D. PUFFER, OF MEDFORD, MASSACHUSETTS.

SAFETY-VALVE.

SPECIFICATION forming part of Letters Patent No. 254,368, dated February 28, 1882.

Application filed November 25, 1881. (No model.)

To all whom it may concern:

Be it known that I, ALVIN D. PUFFER, a citizen of the United States, residing at Medford, in the county of Middlesex and State of Massachusetts, have invented certain new and useful Improvements in Safety-Valves; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

These improvements relate to pressure safety-valves for steam-boilers, soda-water generators, and other uses, the object of this invention being, first, to enable the lever of the valve to be adjusted horizontally, in order that its position with respect to the generator or other object to which it is applied may be varied according to circumstances, and I accomplish this result by pivoting the lever at its base to an upright standard or bracket which is swiveled horizontally to a coupling that makes connection with the interior of the generator, a set-screw or its equivalent being employed to make the standard fast when the desired position has been attained; second, to enable the valve to be readily and quickly removed from over its seat for the purpose of cleaning the outlet port or passage leading from the generator, and I accomplish this by forming the standard or bracket to which the lever is pivoted in two parts, and hinging or swiveling the upper part (which carries the lever) to the lower in such manner that the valve and lever may be swung to one side of or above the valve-seat; third, to enable the valve to rise and fall in a vertical path—that is, strictly at right angles to its seat, and not in an arc of a circle—and I accomplish this by the employment of a valve consisting of an upright cylinder guided in bearings extending laterally over the valve-seat from the upper part of the standard, to which the lever is pivoted and slotted vertically to receive the lever, which is fulcrumed to it in such manner that while the lever rises and falls in the arc of a circle it shall move the valve in a vertical path; fourth, to permit of the necessary rise and fall of the lever and

valve with as little friction between the two as possible, and this I effect by the employment of a fulcrum or pivot composed of an upright vibrating or swinging rod or bar pointed at both ends and stepped at bottom in a pocket in the bottom of the slot in the valve, through which the lever passes, the upper end of the said pivot supporting the weight of the lever, and prevented from escape by entering a pocket in the under side of the lever.

A fifth minor feature in these improvements consists in the employment of a screw passing vertically through the upper end of the valve and into its slot, and terminating at its lower end directly above the lever in line with the vibrating pivot or fulcrum before named, the object of the regulating-screw being on the one hand to prevent accidental separation of the lever and pivot and escape of the latter, and on the other hand to permit the lever to be lifted sufficiently high to permit of removal of the pivot should occasion require.

The drawings accompanying this specification represent, in Figure 1, a vertical section; in Fig. 2, elevation of stop-pin, and Fig. 3 elevation of valve.

Referring to the above-named drawings, the reader will see that A represents a hollow coupling or boss, which is to make connection with the interior of a generator in manner that will be at once understood, this boss rising upward into a column or standard, the extreme upper part, B, of which constitutes the valve-seat of the apparatus, the interior or bore of the boss A being contracted to a small aperture, C, as it approaches such seat.

D in said drawings represents an upright bracket or standard, composed of a vertical bar, a, and lateral horizontal arms b c d, the two upper of such arms—viz., b c—extending over the valve-seat B, while the lower one, d, has a circular opening, which incloses the upper part or neck e, of the boss A in such manner that the entire bracket or standard is capable of rotating about such boss. The body a of the bracket D is formed in two parts, f g, the upper, f, containing the arms b c, before named, and being swiveled to the lower part, g, in such manner as to be susceptible of moving to one side of or above the valve-seat B.

The swivel or hinge between the parts f g

of the bracket may be of various forms. As shown in the present instance it is composed of a vertical tenon, *h*, extending from the under side of the upper portion, *f*, and entering a socket, *i*, in the lower portion, *g*, by which means the upper portion of the bracket and the valve and lever carried by it may be swung to one side of the valve-seat and allow ready access to be had to the latter, should occasion require, for purposes of cleansing or otherwise.

A suitable stop-pin, *j*, is to be combined with the tenon *h*, operating with a notch, *k*, in the lower portion, *g*, of the bracket to determine the extent of movement of the valve away from its seat in one direction, and to insure its juxtaposition with such seat when in position to close the opening *C*.

A modification of the joint between the parts *f* and *g* of the bracket would be a horizontal hinge between the two, which would permit the portion *f* and the valve and lever carried by it to be raised in the arc of a circle above the valve-seat to permit of access to the latter; or the tenon *h* may be adapted to permit the part *f* to rise and fall in a vertical path to permit of separation of the valve and seat.

I do not restrict myself to any precise form of joint between the two parts of the standard.

It frequently happens in applying safety-valves to generators and other vessels that the lever must be placed in a certain position or direction to accommodate it to certain pipes, connections, &c. As it is uncertain in ordinary valves in what position the lever will stand when the brass coupling *A* is screwed home, no certainty can be previously had that the lever will stand in the right position of the lever after the connection is made. It cannot be done, except by loosening the coupling or adding a thickness of washers, until the desired position is attained with the coupling screwed home.

By swiveling the bracket horizontally to the boss *A*, as stated, I am enabled to vary the position of the bracket after the connection with the generator has been made, and arrange the valve-lever in any desired position to avoid or accommodate it to various pipes, connections, &c., and a set-screw, *p*, is to be added to the arm *d* to secure the lever permanently in place when its desired position is ascertained. One modification of the open arm or ring-support *d* would be a pair of curved spring-jaws extending from the standard *D* and embracing the neck *e* of the boss, the ends of these jaws having a clamp-screw, by which they may be tightly clamped about such neck.

The valve is shown at *E* as being in the present instance a straight cylinder or bar disposed vertically over and covering the port *C*, this valve sliding freely in bearings in the ends of the arms *b* *c* before named, and rising and falling with respect to the valve-seat *B* in a vertical plane at right angles to the latter.

The valve-lever is shown at *F* as pivoted at its base by a horizontal pivot, *a'*, to the upper

part of the standard *D*, and passes horizontally through a long vertical slot, *k*, in the valve *E*, and is weighted as usual. The lever *F* is to be provided with scales of divisions and notches, 70 after the manner of scale-beams, and these scales of divisions may be several in number, according to the varying pressures within the generator to which the valve is applied. For instance, as shown in Fig. 1 of the drawings, 75 which is a side view of the lever, one scale may be employed for generators of machines for bottling aerated waters, another for generators or receivers of apparatus for filling siphons with soda-water, another for generators or fountains of soda-water apparatus, &c.

The connection between the lever and valve before named is a novel and useful one. It consists of a vertical pivot or pin, *l*, pointed at both ends and located in the lower part of the 85 slot *k* of the valve *E*, and stepped at bottom in a pocket, *m*, in the bottom of said slot, while at its upper end the pivot *l* sustains the weight of the lever. The lever *F* under the fluctuations of the valve rises and falls in the arc of 90 a circle of which its pivot *a'* is the center, while the valve *E* rises and falls in a vertical plane of movement. The discrepancy between the movements is compensated for by the pivot *l*, which vibrates upon its lower pivot with the 95 minimum of friction.

To prevent the lever *F* from lifting sufficiently high to permit of accidental escape of the pivot *l*, I employ a screw, *n*, which passes through the top of the valve and into its slot 100 *k*, and terminates at its lower end immediately above the lever *F*. When it is desired for any reason to remove the pivot *l* the screw *n* is to be raised far enough to permit the lever to be lifted the necessary distance. 105

A substitute for the screw would be an eccentric pivoted to the upper part of the yoke and adapted to approach closely to or recede from the top of the lever, as occasion required; or a sliding block contained in a vertical passage in the arm *b* above the lever and slotted to receive a horizontal wedge supported in a recess or channel in the said arm *b* may be employed to exert the desired control over the lever in lieu of the screw *n*. 115

I claim—

1. In combination with a valve-seat and safety-valve, an operating-lever and its support, said lever, valve, and support being adapted to turn horizontally for the purpose of removing said valve from said valve-seat. 120

2. In combination with a safety-valve and valve-seat and the operating-lever, the fixed part *g* of the supporting-bracket and the part *f* of said bracket, which is pivoted in part *g* and adapted to turn laterally, carrying the lever and valve away from the valve-seat, substantially as stated. 125

3. In combination with a valve-seat and safety-valve and the operating-lever for the latter, a supporting-bracket consisting of fixed part *g*, pivoted part *f*, and a screw whereby said

parts *f* and *g* may be locked together or released at will.

4. In safety-valves containing a vertical drop-valve and a horizontal lever controlling the same, the valve as composed of a cylinder or bar slotted to receive the lever and moving in a vertical plane, and connected with the lever by a joint, which permits the latter to move in the arc of a circle without disturbing the valve in its strictly vertical pulsations.

5. In combination with a notched safety-valve and lever, a pivot or rod, *l*, pointed at both ends and setting into said valve and lever, and the screw *n*, which prevents said lever from separating too far from said valve.

6. The general physical structure of the entire valve consisting of the hollow base or coupling, by which connection is made with the gen-

erator or other object, the bracket or standard in two parts hinged or swiveled together to permit the valve contained in its swinging part to be removed from over the valve-seat and swiveled horizontally to the base or coupling to permit of any desired adjustment of the valve-lever, and the lever and valve and their connections arranged substantially as described, whereby the lever moves in an arc of a circle and the valve in a vertical plane, the whole co-operating to produce results stated.

In testimony whereof I affix my signature in presence of two witnesses.
